(57) **CLAIM**

The ornamental design for a tap handle, as shown and described.

DESCRIPTION

FIG. 1 is a front view of a tap handle showing my new design, wherein the rear view is a mirror image thereof; and, FIG. 2 is a left side view of the tap handle illustrated in FIG. 1, wherein the right side view is a mirror image thereof. The broken lines in the drawings illustrate the portions of the tap handle that form no part of the claimed design.
